UNITED STATES PATENT OFFICE

2,150,915

SOLE PRESS

Sidney J. Finn, Beverly, Mass., assignor to United
Shoe Machinery Corporation, Paterson, N. J.,
a corporation of New Jersey

Application March 11, 1938, Serial No. 195,355

7 Claims. (Cl. 12—37)

This invention relates to machines for cement-attaching soles to shoes and is illustrated as embodied in a machine of the type disclosed in Letters Patent of the United States No. 2,047,185, granted July 14, 1936, upon application of Ballard et al.

In machines of this type an intermittently rotating turret is provided with a series of pads upon which shoes and soles are placed in position relatively to each other and pressure applied to the shoes. For this purpose there is provided adjacent to each pad a frame pivoted below the pad and carrying a rest to engage the toe of the shoe and an abutment to engage the last, swinging movement of the frame about its axis serving to carry the abutments into and out of position over the shoe. After swinging the frame into upright position the operator depresses a treadle which causes actuation of the rest and abutment by fluid pressure means to apply pressure to the shoe and sole. In the machine of the prior patent the treadle may be operated and the abutments actuated whether or not the frame has been swung into operative position over a shoe. Accidental or unintentional actuation of the abutments when they are in inoperative position is likely to cause breakage or injury to the machine, especially when equipped with welt hold-down apparatus such, for example, as that illustrated in Letters Patent of the United States No. 2,074,834, granted March 23, 1937, upon application of S. J. Finn.

Objects of this invention are to provide means for preventing operation of the shoe-engaging means, viz., the rest and abutment, unless and until the frame carrying these abutments is swung into operative position. In the machine of the Ballard et al. patent, each of the fluid-pressure-operating means for applying pressure to the shoe is provided with a three-position valve the handle of which, when moved to the right, opens the valve to admit fluid pressure to the pressure-applying mechanism. The machine is also equipped with a system in which fluid is circulated continuously including a bypass having a pressure-inducing valve closing of which causes pressure to be furnished to that one of the pressure-applying mechanisms whose three-position valve is in intake position. Depression of the treadle above referred to moves the three-position valve located at the operating station into intake position and closes the pressure-inducing valve, whereupon the pressure-applying mechanism is operated. In accordance with the present invention, means is provided for discon-

nnecting the treadle from the mechanism by which the three-position valve is moved into intake position and means controlled by movement of the swinging frame is provided for again connecting the treadle and the valve-moving mechanism when the frame is swung into operative position. As illustrated, a latch is provided between two parts of the mechanism for communicating movement of the treadle to the three-position valve, which latch is held in inoperative position when the pressure-applying frame is swung rearwardly into its inoperative position and is allowed, by movement of the frame into position over the shoe, to assume its operative position to connect the treadle with the three-position valve so that the valve will be opened when the treadle is depressed.

In the drawings,

Fig. 1 is a fragmentary front elevation of a machine embodying the present invention;

Fig. 2 is a side elevation of the upper part of the machine showing one of the pads and pressure-applying devices;

Fig. 3 is a perspective detail of mechanism shown in Fig. 1;

Fig. 4 is a view similar to Fig. 3 showing the parts in a different position; and

Fig. 5 is a rear view in elevation of some of the parts shown in Fig. 1.

In order that the present invention for rendering the pressure-applying mechanism inoperative when the pressure-applying abutments are not over the pad may be clearly understood, the cooperating parts of the prior construction will be briefly explained, a more complete description being available in the patent first referred to above.

The machine comprises a column 10 upon which is mounted a turret 12 upon which a series of pad boxes, one of which is shown at 14 (Fig. 2), is carried. In the pad box 14 is a yielding pad 15 on which a shoe A mounted on a last L is placed. A swing frame comprising a pair of uprights 16, 18 is pivoted on a horizontal shaft 20 located below the pad 14 and carries an abutment 22 for engaging the cone of the last and a toe rest 24 which, when the frame 16, 18 is in upright position as shown in Fig. 2, are operated to apply pressure to the shoe A located on the pad 15 by a pair of levers 26, 28 pivoted on a shaft 30 mounted in the uprights 16, 18. The rear ends of the levers 26, 28 are engaged by an equalizing lever 32 pivoted on a pin 34 carried by ears 36 fixed to the top of the piston 38 arranged for vertical movement in a cyl-

inder 40. Fluid, for example oil under pressure, is admitted to the cylinder 40 through a pipe 42, and the flow of pressure fluid to the cylinder is controlled by a three-position valve 44 (Fig. 1) which can be operated by a handle 46 or by a link 48. The link 48 is connected to an upright arm 50 of a three-armed lever pivoted at 52 upon the turret 12, the other arms of the lever being designated by 54 and 56. The above-described mechanism is duplicated for each of the eight pads with which the machine is usually provided and, when at the operating station, the above-described mechanism cooperates with the following mechanism which is located only at the operating station.

A pressure control treadle 60 (Fig. 1) when depressed pulls downwardly on a rod 62 and causes a pressure-inducing valve 64 to be closed. This normally open valve is in a bypass between a pipe 65 and a pipe 68 through which oil is circulated by a continuously rotated pump P and, when the valve 64 is closed, the pump draws oil from a tank 70 through a pipe 72 and forces it through a pipe 74 leading to the turret whence it is conducted to each of the three-position valves 44. Depression of the treadle 60 also lowers a head 76 away from a roll 78 on the arm 54 and at the same time operates a lever 80 pivoted thereto at 81 and having a stationary pivot at 82. The left-hand arm 83 of the lever 80, in the prior construction, carries a roll 84, which roll when moved upwardly by depression of the treadle 60 engages the arm 56 and rocks the three-armed lever 50, 54, 56 clockwise to move the three-position valve into intake position whereby pressure fluid is supplied to the pipe 42 to act on the piston 38 and apply pressure to the shoe.

It will now be seen that, if the roll 84 is rendered inoperative to move the arm 56 when the treadle is depressed, the three-position valve will not be opened and pressure cannot be applied to the abutments at the operating station even if the treadle 60 is depressed and the pressure-inducing valve 64 closed. Accordingly the present invention provides means for rendering the roll 84 operative or inoperative to move the arm 56, which mechanism is controlled by the position of the swing frame 16, 18 in such a way that when the swing frame is swung rearwardly to locate the abutments out of position over the shoe the roll 84 is rendered inoperative, and when the swing frame is in its upright position the roll is rendered operative. To this end the mechanism illustrated in Figs. 3, 4 and 5 is provided.

55 It will be seen (Fig. 3) that the left-hand arm 83 of the lever 80 curves down and up again. The rear face of the arm 83 has a rectangular groove 88 formed therein in which a latch 90 is pivoted on a pin 92. A spring 94 (Fig. 4) engages the latch 60 90 above its pivot 92 to urge it rearwardly. The upper end of the latch 90 is cut away to form a latch face 96 which may engage and support the left-hand end of a lever 98 pivoted at 100 between ears 102 formed on the hub portion of the lever 80, 83. It will be seen that in the present construction the roll 84 is mounted by a bolt 103 on the lever 98 instead of on the lever arm 83 as heretofore. A tension spring 104 (Fig. 5) is connected at one end to a pin 106 on the right-hand arm 108 of the lever 98 and at the other end to a pin 110 on the arm 112 secured by a set-screw 114 to the pivot shaft 82 of the lever 80, 83. The spring urges the arm 108 against a stop-screw 116 threaded through a lug 118 on the lever 98 so that, when the lever 98, 104 is positively held

against the stop-screw 116 by the engagement of the latch face 96 under the arm 98, this lever becomes an operative part of the lever 80, 83 and therefore the roll 84 will operate as usual upon depression of the treadle to swing the arm 50 clockwise and, through the link 48, move the handle of the three-position valve 44 to inlet position. If the latch 90 is swung forwardly to disengage its latch face 96 from the lever 98, the lever 98, 104 will cease to be operated by movement of the lever 80, 83 and hence the roll 84 will be inoperative to open the valve 44. This inoperative condition should obtain when the arm 16, 18 is swung rearwardly to permit removal of a shoe and the placing of another shoe upon the pad. For this purpose the shaft 20 is secured to the swing frame 16, 18 by a set-screw 122 and is provided with a rearwardly curved arm 120 secured to the shaft 20 by a set-screw 123. When the swing frame 16, 18 is upright, as in Fig. 3, the latch face 96 will be located under the lever 98 and the machine will operate as usual. When, however, the swing frame 16, 18 is swung rearwardly, as shown in Fig. 4, the arm 120 engages the arm 124 of a yoked lever pivoted at 126 to a stationary part 128 of the machine frame and having below the arm 124 another arm 130 carrying a stop-screw 132 which is in position to engage the latch 90 when the arm 124 is moved forwardly by the arm 120. Thus, when the swing frame 16, 18 is in its rearwardly swung inoperative position, the latch will be held out from under the lever 98 and hence the roll 84 rendered inoperative to operate the valve 44. Reverse movement of the arm 124 is limited and adjusted by a stop-screw 134 threaded through a lug on the lever 124 in position to engage the part 128 of the frame to which the lever is pivoted.

Having thus described my invention, what I claim as new and desire to secure by Letters Patent of the United States is:

1. In a machine for pressing soles upon shoe bottoms, a yielding pad to receive the sole and shoe, pressure-applying means movable into and out of position relatively to the pad to apply pressure to the shoe, means for operating said pressure-applying means, and means controlled by the position of said pressure-applying means for determining whether or not the operating means shall actuate the pressure-applying means.

2. In a machine for applying pressure to shoe bottoms, the combination of a yielding pad to receive a lasted shoe and sole, means for engaging the shoe and last to apply pressure thereto, said means being mounted for movement into and out of position over the shoe, means for operating the shoe and last engaging means when over the shoe to apply pressure to the shoe, and means for rendering said operating means inoperative when the shoe and last engaging means are not over the shoe.

3. In a machine for applying pressure to shoe bottoms, the combination of a yielding pad to receive a lasted shoe and sole, means for engaging the shoe and last to apply pressure thereto, said means being movable from an operative position over the shoe to an inoperative position where they are not over the shoe, means for actuating said shoe and last engaging means when they are in position over the shoe, and means operated by movement of the shoe and last engaging means into their inoperative position to prevent actuation thereof.

4. In a machine for applying pressure to shoe bottoms, the combination of a pad to receive a

shoe and sole, pressure-applying means movable into and out of position over a shoe on the pad, fluid-pressure-operated means for said pressure-applying means, a valve for controlling the application of pressure to said fluid-pressure-operated means, a treadle connected to said valve for operating the valve to admit fluid under pressure to said fluid-pressure-operated means, and means operated by movement of the pressure-applying means out of its operative position over the shoe to break the connection between the treadle and said valve to prevent operation thereof.

5. In a machine for pressing soles upon shoe bottoms, a yielding pad to receive a sole and shoe, pressure-applying means arranged to swing into and out of position relatively to the pad to apply pressure to the shoe, means for operating said pressure-applying means, and means controlled by the position in which the pressure-applying 10 means is located for determining whether or not the operating means will act on the pressure-applying means.

6. In a machine for applying pressure to shoe bottoms, the combination of a yielding pad to receive a lasted shoe and sole, means for engaging the shoe and last to apply pressure thereto, said means being arranged for swinging movement

about a center below the pad into and out of position over the shoe, means for operating the shoe-and-last-engaging means when over the shoe to apply pressure to the shoe, and means operated by said swinging movement for rendering said operating means inoperative when the shoe-and-last-engaging means are not over the shoe.

7. In a machine for applying pressure to shoe bottoms, the combination of a plurality of pressure-applying devices each comprising a pad, means for engaging the shoe and last arranged for movement into and out of position relatively to the shoe, a cylinder and piston for operating said engaging means to apply pressure to the shoe and a valve for controlling admission of fluid under pressure to said cylinder, means for presenting said pressure-applying devices successively at an operating station, a treadle at the operating station, connections from said treadle to said valve for operating each valve in turn as it is presented at the operating station, a latch in said connections through which the treadle is connected to the valve, and an arm operated by movement of said shoe-engaging means acting to release the latch when said means is moved away from the shoe.

SIDNEY J. FINN.
